UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,588, dated August 28, 1894.

Application filed July 28, 1894. Serial No. 518,891. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of an irregular arrangement of flowers and leaves of roses, pinks and 10 oxalis, with small grass-like sprays combined with said flowers and leaves as represented in the accompanying drawing. The border or upper portion of said design is formed of ornamental scrolls connected by a vase-like 15 ornament filled with flowers and leaves of roses, pinks and oxalis, with groups of roses and pinks between said ornaments as shown in the drawing. An ornamental band containing small ornamental scrolls forms the bottom of the border as shown. 20

What I claim is—

The design for wall paper herein shown and described.

Witness my hand this 26th day of July, 1894.

CHARLES BOOZE.
